P. G. PULLOS.
ANTI-RAIL-CREEPING AND RAIL FASTENING DEVICE.
APPLICATION FILED SEPT. 27, 1920.

1,362,508.

Patented Dec. 14, 1920.

UNITED STATES PATENT OFFICE.

PETER G. PULLOS, OF SALT LAKE CITY, UTAH.

ANTI-RAIL-CREEPING AND RAIL-FASTENING DEVICE.

1,362,508.

Specification of Letters Patent. Patented Dec. 14, 1920.

Application filed September 27, 1920. Serial No. 413,130.

To all whom it may concern:

Be it known that I, PETER G. PULLOS, a subject of the King of Greece, residing at Salt Lake City, in the county of Salt Lake 5 and State of Utah, have invented certain new and useful Improvements in Anti-Rail-Creeping and Rail-Fastening Devices; and I do declare the following to be a full, clear, and exact description of the invention, such 10 as will enable others skilled in the art to which it appertains to make and use the same.

This invention relates to an improved rail fastening device sometimes called a tie-plate, 15 and it has for one of its objects to provide a device of this class which is of such construction that it will absolutely prevent creeping and spreading of the rails, thus preventing, to a great extent, accidents 20 which occur from such circumstances.

A further object of the invention is to generally improve upon devices of this class by producing one of extreme simplicity and durability, which is extremely easy to make 25 use of, extremely effective in operation, and comparatively inexpensive to manufacture.

A still further and extremely important object of the invention is to provide a device of the above mentioned class which includes 30 a new and novel locking member which is provided with wedge ribs on its opposite faces, thus making it possible to use the same locking member in either direction of traffic.

Other objects and advantages of the invention will be apparent during the course 35 of the following description.

In the accompanying drawings forming a part of this specification and in which like numerals are employed to designate 40 like parts throughout the same:

Figure 1 is a top plan view of the device constructed in accordance with my invention, the same being shown in use.

Figs. 2 and 3 are sections taken on the 45 lines 2-2 and 3-3 of Fig. 1, respectively, looking in the direction of the arrows.

Fig. 4 is a detail perspective view of the locking member.

Fig. 5 is a bottom plan view of a slightly 50 modified form of the base plate of my device.

Fig. 6 is a detail sectional view taken on the line 6-6 of Fig. 5.

Referring to the drawing wherein the preferred embodiment of my invention is disclosed, the numeral 1 designates an ordi-

nary wooden tie upon which my improved chair or tie-plate 2 is secured by means of spikes or the like 3, the plate 2 being provided at its corners with openings to permit 60 passage of the spikes therethrough. Plate 2 is provided along one edge with an enlarged portion 4 which extends from end to end and has an undercut formed in its inner edge to provide a flange 5 beneath 65 which one edge of the base of the rail 6 is disposed and held. Formed on the opposite end of the plate 2 is a boss 7 which is provided with a screw-threaded opening and has its inner edge inclined from edge to 70 edge and undercut in the manner disclosed. It will be noted that with this construction, when the rail is in place, a tapered space will be provided between the inner edge of the boss and the opposite edge of the base 75 flange of the rail. Placed upon this boss 7 is a locking member 8 in the form of a plate, the same being provided with an elongated slot 9 through which a retaining bolt 10 is passed, the bolt being received in the screw- 80 threaded aperture of the boss 7 and serving to clamp the member 8 in a set position. The plate 8 is provided on its opposite faces adjacent its inner edge with ribs which are tapered, both in the same direction, these 85 ribs constituting wedges which are adapted to be slid into the tapered space between the boss 7 and the adjacent edge of the base flange of the rail 6 to retain the rail in position. It is to be noted that the inner longitudinal edges of the ribs 11 are undercut 90 so that they will effectively engage the undercut portion of the boss 7. Attention is directed to the fact that in case the rail has a tendency to move longitudinally as 95 it does when it creeps, it will carry the member 8 with it and this member thus obtains a more effective wedging action and will eventually stop creeping altogether. Thus the member 8 due to this construction, will 100 be held rigidly in place and will be prevented against moving upward as might otherwise occur. Emphasis is to be laid on the construction of the locking member 8 since it is provided with an elongated slot 105 9 which permits it to have considerable sliding movement to obtain the proper wedging action between the ribs and the base flange of the rail. Furthermore, the provision of the double wedge members 11 which are 110 tapered in the same direction serves to permit the same locking member to be used in

either direction of traffic. Thus, the necessity of employing two different kinds of locking members is entirely obviated.

Provision is made for anchoring plate 2 so as to prevent it from becoming accidentally displaced and permitting possible spreading and creeping of the rails as might otherwise occur. In Figs. 2 and 3 of the drawing, this anchoring means is shown in the form of a plurality of V-shaped ribs 12 which are arranged in parallelism to one another on the underface of the base plate and are adapted to be embedded in the tie 1. In Figs. 5 and 6, I have shown a slightly different construction of anchoring means. By referring to these figures, it will be noted that the anchoring means here shown is in the form of a plurality of diagonal rows of substantially square projections 14. From practical experience, I find that the V-shaped ribs 12 are most advantageous in that they are very easily embedded in the tie either by manual exertion or by the weight of the train which is exerted on them. Hence, this form of anchoring means is very useful in that it is very easy to be placed in effective position on the tie. On the other hand, the type of anti-slipping means disclosed in Figs. 5 and 6 is more advantageous in that constant pressure exerted on the plate from the weight of the passing train will in time embed in the projections in the rail, and when once embedded there is little or no chance of them permitting slipping or creeping of the base plate. So, it will be seen that the V-shaped ribs are advantageous in that they are more easily placed in effective position, but they are not as effective as the other type of anchoring means because there is a chance of them permitting slipping and creeping of the device which is not possible with the construction disclosed in Figs. 5 and 6.

In use, the base plates 2 are placed upon the ties in the usual manner, and the retaining spikes 3 are driven through the holes in these plates to secure them to the ties. Then, the rail is placed in position on the upper face of the base plate in such a manner as to cause one edge of the base flange to become disposed beneath the retaining flange 5 on the base plate. When the rail is in this position, a substantially V-shaped space will be formed between the opposite edge of the base flange of the rail and the inner edge of the boss 7. Now, assuming that the retaining plate 8 has been placed on the boss and the bolt 10 passed through the slot therein and into the screw-threaded aperture in the boss in such a manner as to permit the member 8 to slide, the plate is moved in such a manner as to force the narrow end of one of the ribs in the V-shaped space far enough forward to effectively bind the base flange of the rail be-

tween the adjacent rib 11 and beneath the flange 5. Bolt 10 is not tightened until after the most effective and desired wedging action is obtained, this wedging action becoming more and more effective as the rail, in creeping, moves the member 8. Bolt 10 should be only slightly tightened so member 8 can move to obtain the above result.

From the foregoing description, it will be seen that I have devised an extremely desirable and effective rail securing device which is extremely simple and inexpensive. It is provided with a novel anchoring means which absolutely prevents creeping or slipping of the rail and device, consequently overcoming the possibility of creeping and spreading of the rails due to accidental movement of the tie plate. The locking between the effective wedge rib and inner longitudinal edge of the boss prevents accidental upward movement of the locking member 8 and increases the effectiveness and the rigidity of the device.

A very careful consideration of the foregoing description taken in connection with the accompanying drawing, will enable persons skilled in the art to which the invention relates, to obtain a clear understanding of the same, therefore further description is deemed unnecessary.

Since probably the best results may be obtained with the construction and arrangement disclosed, this construction and arrangement is taken as the preferred embodiment of my invention. However, I wish it to be understood that slight minor changes may be made as long as they do not depart from the spirit of the invention or the scope of the subjoined claim.

I claim:

An anti-creeping rail plate and rail fastening device comprising a base plate provided with anchoring means and on its upper face and along one edge with securing means for receiving one edge of the rail base flange, being also provided on its upper face adjacent its opposite edge with a boss having a screw-threaded aperture extending therethrough, the inner edge of said boss being undercut and inclined from opposite edges to reduce the width thereof at one end, a retaining and clamping plate resting on said boss, being provided with an elongated hole registering with said screw-threaded aperture, and also provided on its opposite faces with wedge ribs having undercut faces to co-act with the undercut portion of said boss, the double wedge ribs permitting the same clamping plate to be used in either direction of traffic, and a clamping bolt passing through the aforesaid elongated hole and into the adjacent screw-threaded aperture.

In testimony whereof I have hereunto set my hand.

PETER G. PULLOS.
